UNITED STATES PATENT OFFICE.

ORNE W. CHAPIN, OF OMAHA, NEBRASKA.

ALINING MEANS FOR TYPE-WRITING SHEETS.

1,109,821.

Specification of Letters Patent.

Patented Sept. 8, 1914.

Application filed April 6, 1914. Serial No. 829,752.

To all whom it may concern:

Be it known that I, ORNE W. CHAPIN, a citizen of the United States, residing at Omaha, in the county of Douglas and State 5 of Nebraska, have invented certain new and useful Improvements in Alining Means for Type-Writing Sheets, of which the following is a specification.

This invention relates to means for maintaining sheets in horizontal alinement found 10 to be useful in connection with typewriting where duplicate or triplicate copies are required. It is often desired that insurance policies, deeds, leases and other like instruments shall be written in duplicate or triplicate by use of typewriting machines, these forms having parallel printed lines, or lines partly printed.

The object of the invention is to provide 20 means which will be convenient in use, so that the typewritten part of the copies produced will be parallel with the printed lines thereof, and that the typewritten parts of the lines of the copies which are partly 25 printed will be in alinement with the printed parts of said lines. The construction and arrangement of parts for this purpose are fully described herein and in the appended claims and illustrated in the accompanying 30 drawing wherein,—

Figure 1 is a view in side elevation or plan, showing a part of a pad or one of the ends of a plurality of connected printed sheets. Fig. 2 is a section on line 2-2 of Fig. 1. Fig. 3 is a sectional view on line 3-3 of Fig. 1. Fig. 4 is an end view in transverse section of the platen of a typewriting machine, one of the sections of sheets with interposed carbon sheets also being shown. 40 Fig. 5 is a plan view of the pad or plurality of connected printed sheets. Fig. 6 is an enlarged detail showing in longitudinal section, the upper end of one of the sections of sheets.

45 Referring now to the drawing for a more particular description, numerals 7 indicate rectangular sheets each provided with substantially parallel lines, as lines *a* each of which, in part, are printed and in part are 50 in blank so that they may bear certain other data to be written thereon, and lines *b* which are unprinted or blank so that they may bear certain other data to be written thereon.

55 As is well known, in the use of typewriting machines, it is quite difficult, except by loss of time, to so arrange the sheets that the

printing on the copies will appear on the lines thereof, the lines of one sheet generally failing to be disposed in the plane of the lines of an adjacent sheet, and in order that the writing on the copies may be on the lines thereof, each sheet is perforated transversely as indicated at 8, on a line substantially parallel with and adjacent to its upper end, and recesses or incisions 9 are made intermediate its longitudinal edges opening on its upper end and also opening on the perforated line to provide a plurality of projecting portions, as the projecting portion 10 disposed midway between the longitudinal edges of the sheet and the projecting portions 11 outwardly of the projecting portion 10.

The sheets are arranged in sections 3 as shown in Figs. 4 and 6; three sheets are used 75 for a section, the number of sheets required for each section, however, not being material, and depending upon the number of carbon copies required. The sheets of each section are disposed one upon another, the lines *a* and *b* and line 8 of perforations of one sheet being disposed, respectively, in alinement with the lines *a* and *b* and lines 8 of the other sheets of said section, and the sheets of each section at their upper ends 80 are connected by any suitable means as by use of mucilage *m*. The sections thus prepared are then disposed one upon another, and by any suitable means as by use of mucilage and the binding strip *c* applied to 90 projecting portions 11, said sections are secured together to form a pad 12. As thus described a section can be conveniently removed from the pad by being torn at that part of the lines of perforation 8 adjacent 95 to projecting portions 11, the middle projecting portion 10 remaining intact with the section, and this projecting portion will then operate to maintain the lines of the sheets of said section in alinement with reference to 100 each other, and will provide an engaging-piece to be disposed between the roller *d* and platen *e* of a typewriting machine, carbon sheets *x* being interposed in the usual manner for producing copies.

105 Since the lines of the sheets of a section are maintained in alinement with reference to each other, the appearance of the copies when typewritten will correspond to the original sheet, and the arrangement of 110 parts as described prevents inconvenience or loss of time during operation.

The sections are preferably disconnected at their lower ends so that the carbon sheets may be employed in the usual manner.

While I have shown two recesses or incisions 9, the number thereof is not material; the projecting portion 10 however should be disposed midway between the longitudinal edges of the sheets so that the section may move suitably when first engaged by the 10 roller and platen.

Having fully described my invention, what I claim and desire to secure by Letters 06 Patent is,

1. In means for the purpose described, the combination of a plurality of rectangular sheets provided with substantially parallel printed lines and incised at one of their ends to provide projecting portions and connected at one of their ends to dispose said 15 printed lines in alinement and to provide a plurality of sections, said sheets having perforations formed therein adjacent to and substantially parallel with their connected 20 ends to open on said incisions, and means for connecting said sections outwardly of said 25 perforations.

2. In means for the purpose described, the combination of a plurality of sections each consisting of sheets provided with printed 30 lines and connected at one of their ends to dispose their printed lines in alinement and perforated on transverse lines adjacent to said connected ends, said sheets being open at their opposite ends to permit carbon 35 sheets to be interposed and incised at substantially right angles to and opening on the lines of perforations to form outwardly 40 thereof a pair of outer projecting portions and an intermediate projecting portion, and means for connecting said sections outwardly of said perforated lines.

3. Means for the purpose described, comprising a plurality of rectangular sheets provided with parallel lines and connected at 45 one of their ends to dispose said lines in

alinement and to provide a plurality of sections, and perforated on lines adjacent to said connected ends, said sheets being incised at substantially right angles to and opening on the lines of perforations to form a plurality of projecting portions, and means for connecting said sections intermediate the longitudinal edges of the sheets and said incisions. 50

4. In means for the purpose described, the combination of a plurality of sections each consisting of rectangular sheets having parallel lines disposed transversely thereof and connected at one of their ends to dispose their lines in alinement, and having longitudinal incisions opening on their connected 60 ends to form a pair of outer projecting portions and an intermediate projecting portion, said sections being connected at their outer 65 projecting portions and each section being provided with perforations extending between its longitudinal edges to open on said 70 incisions so that it may be conveniently separated from said outer projecting portions for providing an outwardly-projecting engaging-member.

5. In means for the purpose described, the combination of a plurality of sections each consisting of rectangular sheets having parallel lines and connected at one of their 75 ends to dispose their lines in a single plane, and incised longitudinally to open on their connected ends to form a plurality of projecting portions, said sections being connected at one of their projecting portions 80 and each of said sections being provided with perforations extending between their longitudinal edges to open on said incisions.

In testimony whereof, I have affixed my signature in presence of two witnesses.

ORNE W. CHAPIN.
